A. STAPLEY

TOY

Filed Feb. 25, 1926

FIG.1.

FIG.2.

FIG.3.

Inventor
Albert Stapley
by Fletcher, Haugh & Co.
Attys.

UNITED STATES PATENT OFFICE.

ALBERT STAPLEY, OF BELLEVILLE, ONTARIO, CANADA.

TOY.

Application filed February 25, 1926. Serial No. 90,660.

My invention relates to improvements in toys, and the object of the invention is to devise a toy which will quickly fix the attention of a child thereon, and which is so 5 designed as to carry educational information to which the child's attention is easily drawn, and with which he thereby becomes familiar without the tedious process of learning in the ordinary way, and it consists essentially of the arrangement and construction of parts as hereinafter more particularly explained.

Fig. 1 is a front elevation of my toy.

Fig. 2 is a rear elevation.

Fig. 3 is a side elevation.

In the drawing like characters of reference indicate corresponding parts in each figure.

1 indicates a main support which is somewhat in the form of a bat provided with a handle 2 by which the toy is held in one hand. 3 and 4 are pins extending outward from the front face of the support 1 in vertical alignment one with the other. 5 is a bar member secured to the outer ends of the pins 3 and 4. 6 is a shaft journalled in the support 1 and in the bar member 5 and extending outward therefrom. 7 is a pulley secured to the shaft 6 between the support 1 and bar 5, and 8 is a pulley secured to the shaft 6 on the projecting portion of the shaft adjacent to the bar 5. 9 is a teeter bar secured to the outer end of the shaft 6 centrally of its length.

10 and 11 are pins extending outward from the bar 9 at each side of the transverse centre and on a longitudinal centre of the bar. 12 and 13 are representations of birds pivotally mounted at 14 and 15 adjacent the outer ends of the bar 9. Washer members 16 and 17 may be inserted between the body portions of the members 12 and 13 and the bar 9 so as to permit of the free movement of such members around the pivot supporting pins 14 and 15. The beaks of the members 12 and 13 rest normally upon the pins 10 and 11.

18 is a resilient connection between the pulley 8 and a pin 19 extending from the support 1, such resilient connection being preferably in the form of an ordinary elastic band extending at its lower end through the slit opening 20 at the outer end of the pin 19 and secured at its upper end in the

slit opening 21 extending across the face of 55 the pulley 8 as indicated by dotted lines in Fig. 1.

22 is a cord secured at one end to the pulley 7 at 23 and wound thereon, the free end depending through an eye 24 carried 60 by the support 1 and provided at its extreme lower end with a pull handle 25. 26 is a representation of a clock provided with clock hands 27 and 28 which may be turned to any desired position so as to teach the 65 child how to tell the time.

On the back of the support are arranged the letters of the alphabet and the numerals 70 preferably arranged in vertical rows so as to be readily discernible to the child.

In operating the toy the supporting handle 2 is held in one hand and the pull handle 25 pulled so as to revolve the pulley 7 and the pulley 8 so as to unwind the cord 22 off the pulley 7 and wind the resilient band 28 75 onto the pulley 8. By alternately pulling upon or releasing the handle 25 a rapid teetering motion is given to the bar 9 so that the bird members 12 and 13 are quickly reciprocated on their pivots 14 and 15 80 carrying the beak portions thereof alternately in and out of contact with the pins 10 and 11 giving to the bird members a pecking movement, the rapid impact of the beaks against the pins 10 and 11 quickly calling 85 the attention of the child thereto so as to hold his attention and thereby enable the teacher to gradually impart to him the knowledge to be gained upon the various 90 matters which might be placed on the front or rear faces of the support 1, such as the clock representation, letters of the alphabet and the numerals.

What I claim as my invention is:

1. A toy comprising a bat like support, a 95 shaft extending outward therefrom, a teeter bar secured to the shaft centrally of its length, pins extending outward from the bar at each side of its centre, bird members pivotally mounted on the ends of the bar and having their beaks resting upon the aforesaid pins, and means for rapidly turning the shaft in opposite directions so as to give a teetering action to the bar and a pecking action to the birds against the pins.

2. A toy comprising a bat like support, a 100 shaft extending outward therefrom, a teeter bar secured to the shaft centrally of its

length, pins extending outward from the bar at each side of its centre, bird members pivotally mounted on the ends of the bar and having their beaks resting upon the aforesaid pins, a pair of pulleys secured to the shaft, a pull cord secured and wound upon one pulley, an elastic member connected to

the other pulley at one end and to a stationary support at the opposite end and adapted to be wound upon said pulley when the aforesaid pull cord is pulled to unwind upon its supporting pulley.

ALBERT STAPLEY.
